UNITED STATES PATENT OFFICE.

NETTIE M. LADD, OF LEESBURG, OHIO.

STOVE-MAT.

1,193,399.

Specification of Letters Patent. Patented Aug. 1, 1916.

Application filed April 12, 1916. Serial No. 90,695.

To all whom it may concern:

Be it known that I, NETTIE M. LADD, citizen of the United States, residing at Leesburg, in the county of Highland and State 5 of Ohio, have invented certain new and useful Improvements in Stove-Mats, of which the following is a specification.

This invention relates to improvements in stove mats and is designed to be used in connection with gas, gasolene, or oil stoves to place over the burners of such stoves particularly such as have large and spreading burners for the purpose of reducing the area of the flame when small utensils are to be 10 heated that would be endangered in whole or in part by the flames mounting the sides of said utensils and melting, burning, or otherwise injuring portions thereof.

With this object in view, the invention 20 consists of a sheet of iron and a sheet of asbestos connected together and having a central opening for the passage of a flame from a gas, gasolene, or oil stove, the exterior of a utensil placed upon said article 25 being protected from the flame by the surrounding surface of the mat.

A further object of the invention is to provide a stove mat made of sheet metal such as iron and a fire resisting material 30 particularly asbestos and connect these two sheets in such a manner as to prevent separation thereof and so form them that while serving to protect small utensils and other vessels from becoming overheated and damaged, will permit the contents of said utensils to be thoroughly heated and receive the 35 full intensity of the heat or as much thereof as is necessary to cook or boil that which they may contain.

Referring to the accompanying drawings, 40 Figure 1 is a face view of one form of the mat. Fig. 2 is a cross sectional view of the same on the line 2—2 enlarged. Fig. 3 is a similar view on the line 3—3.

Referring to the drawing by numerals, 45 indicates an annular plate of sheet metal such as iron having a central opening 11 therethrough which may be of any desired size and shape, but preferably circular, as 50 shown. Projecting inwardly from the edge of the opening 11 are a plurality of fingers 12 which are preferably pointed as shown, and spaced apart a short distance. Near

the outer edge of the plate 10 is a circular row of openings 13, these also are of triangular form and are formed by cutting or punching said metal on two sides thereof and pushing the resulting tongue 14 downwardly. These openings 13 which as before stated are triangular have their bases parallel with the periphery of the plate and their apices pointed toward the opening 11. The fingers 14 will therefore have their pointed ends pointed in the same way.

Against the under side of the plate 10 between the fingers 12 and 14, is placed an annular sheet of asbestos or an equivalent material 15, the edges of which coincide respectively with the bases of the openings 13 and the boundary edge of the opening 11. 65 Over the edges of the asbestos thus placed, the fingers 12 and 14 are folded as clearly shown in Figs. 2 and 3 and pressed closely in place. These fingers form a strong, 70 secure, and safe fastening for the asbestos, 75 which latter may be subjected to an unusual amount of rough usage without hurting or injuring the mat. The outer edge 16 of the plate 10 is rolled or folded under as shown in Figs. 2 and 3 to stiffen and strengthen 80 the mat and to make the same more secure and less dangerous to those handling the same.

Having thus described the invention what is claimed is:

1. A stove mat comprising an annular sheet of thin metal, a like sheet of fire resisting material superposed against the same, a circular row of fingers on the inner edge of the metal adapted to engage the inner 90 edge of the fire resisting sheet, and a similar row of fingers near the outer edge of the metal sheet to clamp the outer edge of said fire resisting sheet.

2. A stove mat comprising an annular sheet of metal having a row of fingers projecting radially from its inner edge, a like row of fingers within the outer edge cut from said sheet and bent downwardly, and an annular sheet of fire resisting material 100 superposed against one side of the metal sheet and secured in place by folding said fingers over the edges of said fire resisting sheet.

3. A stove mat comprising an annular sheet of thin metal having a row of pointed

fingers projecting radially from its inner edge and an inwardly turned bead on its outer edge, a circular row of fingers within said beaded edge cut from said sheet and bent downwardly, and an annular sheet of asbestos superposed against one side of the metal sheet and fitted between its inner circular edge and the outer row of fingers and

secured in place by folding said fingers over the edge of the asbestos sheet.

In testimony whereof I affix my signature in presence of two witnesses.

NETTIE M. LADD.
